UNITED STATES PATENT OFFICE.

WILLIAM H. OSTRANDER, OF CHICAGO, ILLINOIS, ASSIGNOR TO NOVELTIES INCORPORATED, OF CHICAGO, ILLINOIS, A CORPORATION OF ILLINOIS.

CARDCASE.

Application filed June 25, 1928. Serial No. 288,041.

My invention relates to card cases and more particularly to cases from which cards such as business and calling cards may be readily unsheathed.

5 In general, one of the primary objects of my invention is to provide a durable, compact and economically constructed case of ornate design which is equipped with effective and conveniently operable means for partially unsheathing a single card from a stack thereof, whereby ready access may be had to said card.

More specifically, an object of my invention is to provide a card case of the instant 15 nature which may be conveniently carried in a user's pocket, and which is provided with effective means for engaging the edge of a contained card and thereby cause the partial unsheathing of said card, said means being 20 conveniently operable externally of the case.

A still further object of my invention is to provide a compact and neatly appearing case which will protect a quantity of cards from being soiled, means being provided for successively ejecting single cards from the container, said means being designed to engage 25 the card without defacing the same, one end of the case being formed so as to positively direct a card acted upon by the ejecting means 30 to a restricted opening or slit in the case.

Still more specifically, my invention contemplates the provision of a card case of practical construction which may be conveniently refilled by opening the end thereof and is 35 further provided with conveniently operable means in the form of a leaf spring, one end of which supports a manually operable button and the other end a shoulder for engaging the edge of a contained card, thereby presenting 40 a card ejecting device which is not only effective in operation but which is of simple and economical construction.

These and other objects will be more apparent from the following detailed description 45 when considered in connection with the accompanying drawing wherein:

Figure 1 is a plan view of a card case embodying features of my invention, a portion 50 of the wall thereof being broken away to more clearly disclose the construction thereof;

Figure 2 is a longitudinal central sectional view taken along the line 2-2 of Figure 2 showing the card ejecting device in its retracted position;

Figure 3 is a view similar to Figure 2 dis-

closing the ejecting means in its advanced card ejecting position;

Figure 4 is an enlarged fragmentary sectional view disclosing the manner in which the button is secured to the leaf spring;

Figure 5 is a perspective view of the leaf spring detached from the case, the button being shown disassociated from the spring in order to more clearly show the manner in which said button is applied thereto;

Figure 6 is a perspective view of the case as viewed from the discharge end thereof; and

Figure 7 is an enlarged detailed sectional view of the discharge end of the case as viewed in Figure 2.

Referring now to the drawing wherein like numerals have been employed to designate similar parts throughout the various figures, it will be observed that one embodiment of my invention includes a card case which comprises a casing 2 and a cover member 4 which is hingedly mounted upon said casing 2 at the point indicated by the numeral 6. The casing 2 is of a size which will permit of its being conveniently carried by a user and which will accommodate the usual sizes of calling or business cards 8. It will be observed that when these cards are completely sheathed within the casing the intermediate portions of the innermost edges of said cards will be free from engagement with the end wall 10 of said casing by reason of the fact that this end wall is bulged outwardly. By providing this space between the inner edge of the uppermost card, Figure 2, and the wall 10, the free extremity of a leaf spring 12 which is formed with a shoulder 14 is adapted to automatically be carried into gripping or card engaging position, as clearly shown in Figure 2.

This leaf spring 12 forms an element of my card ejecting device which I have indicated generally by the numeral 16. This device also includes a button or cap 18 which is adapted to be conveniently secured to the leaf spring 12 in the manner clearly shown in Figures 4 and 5. It will be seen that a portion of the body of the spring is struck out so as to present a projection 20, said projection having recesses 21 provided at each extremity thereof. A slit 22 provided in the top wall of the casing 2 is designed to receive the projection 20 and serves as a means for guiding the leaf spring 12 as it is reciprocated within

the casing. A small marginal section 23 of the button 18, Figure 5, is bent outwardly to permit the projection 20 to be inserted within the opening 24 of said button and after 5 the parts have been thus assembled and subjected to slight compression, said button will be secured in a fixed position upon the projection, as clearly shown in Figure 4. By 10 having the recess 21 V-shaped said button will be positioned in spaced relation with respect to the body of the leaf spring 12 and juxtaposed with respect to the external surface of the casing. It will be seen that the free portion of the spring 12 which carries the shoulder 14 is sufficiently flexed so as to constantly bear downwardly against the inner ends of the cards 8. This resilient engagement of 15 the spring with the cards not only insures the engagement of the uppermost card by the shoulder 14 when the ejecting device is moved forwardly, but also serves to maintain the entire pack of cards in an orderly fixed position within the casing. Obviously the depth 20 of the shoulder 14 should be less than the thickness of the individual card so as to positively insure the selection and ejection of a single card in response to each forward movement of the ejecting device 16.

The cover 4 is provided with a restricted 30 opening or slit 26 to permit a card to be partially unsheathed in response to the actuation of the ejecting device and in order to insure the proper presentation of individual cards to the opening 26, I form the section 28 of the 35 cover, Figures 2, 3 and 6, arcuately. It will thus be apparent that as each card is moved forwardly and carried into engagement with the cover section 28, said card will be guided upwardly into registration with the opening 40 26. At a point oppositely disposed from the hinge 6, I form an indentation 30 in the cover 4, Figure 1, and a companion indentation within the casing 2 and in this manner I provide a means for conveniently securing the 45 cover in closed position. Obviously other convenient forms of snap locks might be employed for the same purpose. In the top wall of the casing an indentation or projection 32 is pressed inwardly from said wall. 50 This projection 32 serves as a means for shielding a tip portion 34 of the spring 12, as shown in Figures 2 and 3. By providing the projection 32, the possibility of carrying a card into engagement with the tip portion 55 34, when the spring 12 occupies its advanced position, is positively precluded because the tip portion will then be lodged adjacent said projection, as clearly shown in Figure 3. Thus cards may be freely inserted within the 60 case.

From the foregoing it will be understood 65 that my invention provides a very conveniently operable, compact and durably constructed card case. Cards may be readily inserted and upon

each retraction of the ejecting device 16 the shoulder 14 thereof will become lodged behind the uppermost card and upon the advancement of the ejecting device said card will be moved forwardly and guided to the 70 opening or slit 26 through the agency of the arcuate cover section 28. Thus an individual card will be positively ejected or partially unsheathed from the casing in response to each forward movement of the button 18. It will 75 be apparent that my ejecting mechanism requires a minimum number of parts and is of very simple and inexpensive construction and it will also be apparent that the surface portion of the cards is not grippingly engaged 80 by the leaf spring 12 and hence the possibility of defacing said surfaces in the process of unsheathing the card is positively precluded.

Although a specific embodiment of my invention has been described in connection with the disclosure in the drawing, it will be understood that my invention is capable of many other modifications and therefore should be limited only by the scope of the appended 90 claims.

Having thus described my invention, what I claim as new and desire to secure by Letters Patent is:

1. In a card case of the class described, a 95 container for retaining a supply of cards, a unitary cover member removably mounted at one extremity of the container to permit the insertion of cards within the container, said cover member having an opening to permit the ejection therethrough of an individual card, and provided with a smooth inclined surface for directing a card into registration with said opening, and resilient means associated with the container for selecting and engaging the inner edge of an individual card and for advancing said card toward the opening in the cover.

2. A card case of the class described, including a container for conveniently holding a pack of cards, a cover member at one end of said container, said cover being hingedly mounted upon the container to permit the insertion of cards within the container and having a restricted opening to permit the ejection therethrough of an individual card, and having an inclined surface for directing a card into registration with said opening, and a leaf spring slidable within the container having a card engaging shoulder at one extremity thereof, the resiliency of the spring serving, when said spring occupies its retracted position, to positively carry the shoulder into operative position with respect to the inner edge of the adjacent card, thereby enabling an individual card to be advanced and ejected through the opening in the cover in response to the shifting of the leaf spring within the container.

3. In a card case of the class described, a flat type container for retaining a supply of 130

- cards, a removable cover at one end of the container provided with a restricted opening to permit the ejection therethrough of an individual card, and having an inclined surface for directing a card into registration with said opening, and a leaf spring slidable within the container, one extremity thereof being folded upon itself so as to position the terminating edge in operative relation with respect to the inner edge of an adjacent card, thereby enabling said individual card to be advanced in response to the engagement therewith of said terminating edge, the surface presented along the line of fold being adapted to slide freely over the surface of the cards during the retraction of the leaf spring. 35
- 5 5. In a card case of the class described, a flat type container for retaining a supply of cards, a resilient member slidable within the container and operable externally thereof for engaging the inner edge of individual cards to cause the unsheathing thereof, and an end wall provided in said container which is formed with a space at the intermediate portion thereof to permit the inner extremity of the slidable member to be operatively positioned with respect to the inner edge of the cards when said resilient member is moved to its retracted position within the container and provided with an abutment disposed from said intermediate space for positively abutting the inner edges of the cards to insure the presence of said space. 40
- 10 6. A card case of the class described, including a container for conveniently holding a pack of cards, a cover member removably mounted at one end of said container to permit the insertion of cards within the container and having a restricted opening to permit the ejection therethrough of an individual card and having an inclined surface 45
- 15 7. A card case of the class described, including a container for conveniently holding a pack of cards, a cover member removably mounted at one end of said container to permit the insertion of cards within the container and having a restricted opening to permit the ejection therethrough of an individual card and having an inclined surface 50
- 20 8. A card case of the class described, including a container for conveniently holding a pack of cards, a cover member removably mounted at one end of said container to permit the insertion of cards within the container and having a restricted opening to permit the ejection therethrough of an individual card and having an inclined surface 55
- 25 9. A card case of the class described, including a container for conveniently holding a pack of cards, a cover member removably mounted at one end of said container to permit the insertion of cards within the container and having a restricted opening to permit the ejection therethrough of an individual card and having an inclined surface 60
- 30 10. A card case of the class described, including a container for conveniently holding a pack of cards, a cover member removably mounted at one end of said container to permit the insertion of cards within the container and having a restricted opening to permit the ejection therethrough of an individual card and having an inclined surface

In witness whereof, I have hereunto subscribed my name.

WILLIAM H. OSTRANDER.
